PORTABLE MIXING PLANT

William E. Prout, Youngstown, Ohio, and John Yount, Pittsburgh, Pa.

Application December 17, 1938, Serial No. 246,344

6 Claims. (Cl. 259—153)

This invention relates to a mixing plant for mixing proportioned quantities of aggregate and bituminous materials to provide a mixture suitable for road paving operations and the invention has as its primary object the provision of a plant for the purpose stated which is efficient in use, economical to construct, and which may readily be transported from place to place with a minimum of labor, equipment and time.

Although heretofore various arrangements and expedients have been adopted to render plants of the above type portable, a consideration of the prior structures will render apparent their limitations and disadvantages and it is, accordingly, a more specific object of the invention to provide a portable road metal mixing assembly in which the shortcomings of the prior arrangements are obviated. The utility involved in the portability of the plant is predicated, primarily, in the ability to maintain the source of mixed paving materials close to the road building or maintenance operations in which the material is used, thus reducing the length of vehicular haul required. For maximum efficiency it is necessary that the plant be capable of being converted from its operating condition to its transporting condition and vice versa in a short period of time and without the use of any special equipment. Likewise, the plant, when in compacted condition for transporting, should be capable of being transported by a readily available traction device. When assembled for operation, the plant must deliver the mixed material at a height convenient for loading onto trucks and as it is impractical to employ elevating means to lift the material, the common practice is to elevate the hoppers, batchers and mixing mill assembly so that the component materials flow into the mill and the mixed material flows into the truck by gravity. Such a unit, however, is too unstable for transporting and too high for allowable road clearances and therefore some means must be provided to readily raise and lower the assembly mentioned and it is therefore another object of the invention to provide an arrangement whereby the number of elements and total weight required to be raised and lowered is reduced to a minimum.

A further object of the invention is the provision of improved means for raising and lowering the material mixing mill and essential ancillary equipment.

Still another object of the invention is the provision of an improved frame structure for supporting the mill, hoppers, motor and other elements constituting the mixing plant.

Yet another object of the invention is the provision of improved supporting and tractive means for the plant for both fixed and mobile positions.

These and other objects and advantages of the invention will become apparent from a consideration of the following detailed specification and the accompanying drawings wherein there is specifically disclosed a preferred embodiment of the invention.

In the drawings:

Figure 1 is a side view of a portable mixing plant constructed according to the teachings of my invention and shows the plant assembled in operative position;

Figure 2 is a side view of the plant of Figure 1 in transportable collapsed condition and illustrates the manner in which the plant is moved;

Figure 3 is a cross-sectional view taken along the line 3—3 of Figure 1 looking in the direction of the arrows;

Figure 4 is a fragmentary view showing the means employed to raise and lower the frame section which carries the mixing mill;

Figure 5 is a top view of hoisting mechanism of Figure 4; and

Figures 6 and 7 are structural details of the plant supporting frame.

A plant for preparing road paving materials, as concerns the present invention, consists essentially of a hopper for storing gravel or other aggregate, a batcher for weighing out the aggregate, a batcher for the component bituminous material and a mixing mill, commonly termed a "pug" mill for thoroughly intermixing the aggregate and bituminous binder. Referring to Figure 1, which illustrates such a plant set up for operation, these elements are schematically shown at and designated as 10, 11, 12 and 13, respectively. In operation, slag, gravel, or other aggregate material is conveyed to the hopper 10 by any suitable means, as the chain bucket hoist 14 which extends down into or below any suitable source of supply and which is preferably driven by a motor 15 supported on a structural member 16 interconnecting the frame of the hoist and the frame of the plant proper. In accordance with usual practice, the hopper 10 may be provided with two compartments 10a and 10b to store different kinds or grades of material and in actual practice the hoist 14 extends considerably above the top of hopper 10 to a point more centrally located, thereby enabling delivered material to be selectively diverted into one or the other of the compartments by means of a baffle as is well understood in the art.

In carrying out our invention, the frame supporting the various parts of the mixing plant is constructed of three separable sections, designated generally on the drawings as A, B and C.

5 The outer or end sections A and C each comprise a pair of spaced parallel upwardly extending members 18, H-shaped in cross section and so oriented that channels of the members of one frame section face channels of the members of 10 the other frame section to provide, in effect, guideways for the slideable support of corner post members of the center frame section B. Rigidly secured to the members 18 of the frame section A and extending horizontally therefrom adjacent the lower ends thereof is the base 19 which is held in position by the diagonal braces 20 secured at their lower outer ends to the outer end of the base 19 and at their upper inner ends to the upper portions of the adjacent members 15 18. Base 19 may conveniently support the pug mill driving motor 21 although it should be understood that this motor may be mounted on the center frame section C along with the mill or at other locations on the assembly. A housing 22 20 may be built over the base 19 to house and protect the motor 21, or other electrical or mechanical equipment of the plant assembly. Supporting the base 19 is the pair of road engaging wheels 23 which are preferably doubly pneumatic 25 tired and spring mounted in a manner common to vehicular construction.

Rigidly secured to the members 18 of the frame section C and extending horizontally therefrom adjacent the lower ends thereof is the structural platform 25 which is rigidly held in proper position by the braces 26 which are connected at their outer ends to the outer end of the platform 25 and at their inner ends to the upper portions of the adjacent members 18. Platform 25 is provided, primarily, to provide means whereby the plant, when in collapsed transportable condition (see Figure 2), may be coupled with a motor tractor of conventional design and to this end a beveled disk 33 having a centrally disposed downwardly extending pin 34 is secured to the underside of the platform 25. As shown in Figure 2, the disk 33 and pin 34 are adapted to cooperate with a coupling 35, commonly termed a "fifth wheel," of a conventional tractor 36. Platform 25 may also be utilized to support a tank 27 for the storage of asphaltic oil or other bituminous material used in the preparation of the road metal material and, in accordance with usual practice, a heating means, schematically shown at 28, may be built into the tank 27. A motor driven pump 30 having an inlet pipe 31 connected with the tank and an outlet pipe 32 extending to the bituminous material batcher 12 is operative to pump the material from the tank and may also be conveniently supported on the platform 25.

The intermediate frame section B consists of a box-like assembly of structural members including four spaced corner posts 40 which posts 65 are H-shaped in cross-section and have outer dimensions sufficiently small to nest within the channels of the frame members 18. Note Figures 5 and 6. A platform 41 rigidly connects the lower ends of the columns 40 and horizontally extending frame elements 41u ties together the upper ends of the members 40 and provides an immediate support for the aggregate hopper 10. The latter is provided with a readily removable top portion 10c which is removed when the plant 70 is collapsed for transportation and two outlet 75

valves 51a and 51b for controlling the flow of materials from the compartments 10a and 10b respectively. The valves 51a and 51b are controlled by any suitable hand operating means 52a and 52b respectively. Aggregate batcher 11 5 is supported beneath the hopper 10 on a scale beam shown schematically at 54 and an indicator 55 may be employed to show the amount of material in the batcher. A valve 56 is provided to control the flow of material from the batcher 11 into the pug mill 13. The bituminous material batcher 12 is likewise provided with means to indicate the weight of material therein but as the aggregate and bituminous material weighing means form no part of the invention they have 10 been omitted in part for sake of brevity. A manually controlled valve 57 controls the flow of the bituminous binder from the batcher 12 into the pug mill. A pair of side members 42 intermediate the upper and lower ends of the frame section 15 B may be provided to lend rigidity to the structure.

Pug mill 13, being of conventional design, is provided with a pair of parallel shafts 43 each having a plurality of mixing blades 44 extending radially outward therefrom. See Figures 1, 2 and 3. Shafts 43 are rotated in opposite directions by the gear trains 47 which is connected with the jack shaft 49 mounted on frame section A. A link chain 48 connects the jack shaft 30 with the gear train and a belt or chain 50 connects the motor 21 with the jack shaft. When the frame is to be collapsed for the transporting of the plant, the chain 48 is first removed. With the center frame section B in elevated position 35 as shown in Figure 1 of the drawings, the platform 41 is elevated sufficiently to allow a motor truck 90 of conventional design to pass underneath thereof. As the mixing of a batch of the road making material is completed, a gate 45 in 10 the lower wall of the pug mill 13 is opened by any suitable means, as the steam cylinder 46, and the mixed material falls into the body of a truck positioned below.

Referring now to Figures 1, 4 and 5, the means 45 employed to raise and lower the center frame section B consists of a pair of conventional chain blocks 70 coupled with a pair of parallel shafts 74 about which are wound the lifting cables 80. Chain blocks 70 are conveniently supported on the frame sections A and C, respectively, either by means of a bracket 71 or by other suitable means and are each provided with a manually engageable endless chain 72 and a slow speed driving shaft 73. The latter are coupled with 50 the shafts 74 by the chains 75 trained over sprockets keyed to the shafts involved. As shown in Figure 5, the shafts 74 are journaled on the vertical columns 18 of the frame sections A and C and are positioned so as not to interfere with 55 vertical movement of the section B. Each shaft 74 is provided with one or more drums 76 on which is wound the cables 80, the cables being looped under pulleys 79 carried by parallel shafts 77 secured to the lower end of the frame section 60 B. The fixed ends of the cables 80 are anchored to the fixed frame sections A and C at 81. It should be obvious that, with the parts assembled, as shown, manipulation of the chains 72 will result in the center frame section B being raised 65 or lowered relative to the end sections A and C.

To provide additional support for the hopper, batchers, and mill when the plant is in operation, foot members 61 (see Figure 1) having bottom load bearing webs 61a are attached to the lower 70 75

ends of the H-columns 18 by means of the splice plates 62 and bolts 63. Note Figure 7. When the plant is prepared for transportation, the foot members 61 are removed.

To lend rigidity to the structure when assembled for operation, an X brace 60 is secured to each side of the assembly which braces are bolted at their lower ends to the H-columns 18 and at their upper ends to the corner posts 40 of the center frame section B. In addition to this tie, the sections are further secured together by a plurality of bolts 64 which pass through portions of the nesting members 18 and 40. Note Figure 6. When it is desired to lower frame section B, the X braces are detached from their upper shown position and lowered to a position where both upper and lower ends are bolted to the H columns 18. Bolts 64 are then removed and the section B including the members 40 is then free to be lowered by action of the chain blocks in the manner described above. Upon completion of the lowering operation, bolts 64 are reinserted in appropriately provided aligned holes to again securely bolt the frame sections together after which the X braces may be removed, if desired. To prevent binding between the H members 18 and 40 during relative vertical movement of the section B, a metallic bar 65 is welded or otherwise suitably secured in each of the channels of members 18 into which members 40 will extend. The channels provided by the flanges of members 18 and the bars 65 provide satisfactory guides for the slidable movement of the center section when the latter is being raised or lowered. The guides thus provided are maintained in their proper spaced parallel relation by the X braces 60. The steps 68, providing ready access to the mill and various controlling devices of the plant when the plant is in operation, are detachably secured to the frame and are removed when the plant is prepared for transportation.

It should now be apparent that we have provided an apparatus which accomplishes the objects initially set out. With a minimum amount of labor and without the use of any separate equipment, the plant may readily be collapsed and prepared for movement to a new location of use. Such preparation is accomplished simply by lowering a portion of the frame and backing the fifth wheel of a conventional motor tractor under a portion of the same whereby tractive force may be applied. When collapsed, the plant, including the wheels 23, is similar in general organization, weight distribution and size to a conventional large semi-trailer used for hauling freight and as such can be rapidly moved from place to place over all highways suitable for truck traffic without the necessity of any special preparation or precaution. The above specifically disclosed embodiment of our invention should be considered as illustrative only as obviously innumerable changes may be made therein without departing from the spirit or scope of our invention.

What we claim is:

1. In a portable mixing plant the combination of an intermediate box-like frame for the support of a material mixing device, a material mixing device carried in the lower portion of said frame, end frames extending horizontally outward from either end of said intermediate frame, road engaging wheels attached to and supporting one of said end frames, means carried with the other of said end frames to engage and be sup-

ported by a motor tractor whereby said plant when in transportable condition assumes generally a semi-trailer form, and means to elevate said intermediate frame relative to said end frames to assemble said plant for operation whereby sufficient vertical interval may be attained between the normal supporting surface of the plant and the bottom of the intermediate frame to permit conventional material transporting trucks to pass underneath the intermediate frame. 5

2. In a portable mixing plant the combination of an intermediate box-like frame for the support of a material mixing device, a material mixing device carried in the lower portion of said frame, said frame being provided with vertically extending end members on either end thereof, end frames extending horizontally outward from either end of said intermediate frame, said end frames having vertically extending members normally abutting said vertically extending members of said intermediate frame, road engaging wheels attached to and supporting one of said end frames, means carried with the other of said end frames to engage and be supported by a motor tractor whereby said plant when in transportable condition assumes generally a semi-trailer form, and means to elevate said intermediate frame relative to said end frames to assemble said plant for operation whereby sufficient vertical interval may be attained between the normal supporting surface of the plant and the bottom of the intermediate frame to permit conventional material transporting trucks to pass underneath the intermediate frame. 10 15 20 25 30 35

3. In a portable mixing plant the combination of an intermediate box-like frame for the support of a material mixing device, a material mixing device carried in the lower portion of said frame, end frames extending horizontally outward from either end of said intermediate frame, road engaging wheels attached to and supporting one of said end frames, means carried with the other of said end frames to engage and be supported by a motor tractor whereby said plant when in transportable condition assumes generally a semi-trailer form, and means to elevate said intermediate frame relative to said end frames to assemble said plant for operation whereby sufficient vertical interval may be attained between the normal supporting surface of the plant and the bottom of the intermediate frame to permit conventional material transporting trucks to pass underneath the intermediate frame. 40 45 50 55 60

4. In a portable mixing plant the combination of an intermediate box-like frame for the support of a material mixing device, a material mixing device carried by said frame, said frame being provided with vertically extending end members on either end thereof, end frames extending horizontally outward from either end of said intermediate frame and being provided with channeled vertical members adapted to receive the outer edges of the said vertically extending members of said intermediate frame, road engaging wheels attached to and supporting one of said end 65 70 75 80 85 90 95 98 99 100

- frames, means carried with the other of said end frames to engage and be supported by a motor tractor whereby said plant when in transportable condition assumes generally a semi-trailer form, and means to move said intermediate frame vertically along said channeled members to assemble said plant for operation whereby sufficient vertical interval may be attained between the normal supporting surface of the plant and the bottom of the intermediate frame to permit conventional material transporting trucks to pass underneath the intermediate frame.
5. In a portable mixing plant the combination of an intermediate box-like frame for the support of a material mixing device, a material mixing device carried by said frame, said frame being provided with vertically disposed members on either end thereof, end frames extending horizontally outward from either end of said intermediate frame and being provided with vertically disposed members overlying said vertically disposed members of said intermediate frame when the plant is in collapsed condition for transportation, a power device for driving said material mixing device supported by certain of said end frames, road engaging wheels attached to and supporting one of said end frames, means carried with the other of said end frames to engage and be supported by a motor tractor whereby said plant when in transportable condition assumes generally a semi-trailer form, and means to elevate said intermediate frame relative to said end frames to assemble said plant for operation whereby sufficient vertical interval may be
- 10 15 20 25 30

attained between the normal supporting surface of the plant and the bottom of the intermediate frame to permit conventional material transporting trucks to pass underneath the intermediate frame.

6. In a portable mixing plant the combination of an intermediate box-like frame for the support of a material mixing device, a material mixing device carried by said frame, said frame being provided with vertically disposed members on either end thereof, end frames extending horizontally outward from either end of said intermediate frame and being provided with vertically disposed members overlying said vertically disposed members of said intermediate frame when the plant is in collapsed condition for transportation, road engaging wheels attached to and supporting one of said end frames, means to movably support the other of said end frames, the relation of the parts being such that when the plant is in collapsed transportable condition said intermediate frame is substantially horizontally aligned with said end frames, and means to elevate said intermediate frame relative to said end frames to assemble said plant for operation whereby sufficient vertical interval may be attained between the normal supporting surface of the plant and the bottom of the intermediate frame to permit conventional material transporting trucks to pass underneath the intermediate frame and between said end frames.
